DESIGN FOR A TERMINAL LINK FOR AN EXPANSIBLE WRIST WATCH BRACELET OR SIMILAR ARTICLE

Eric G. O. Anderson, Cranston, R. I., assignor to
Everfine Jewelry Manufacturing Company,
Providence, R. I., a corporation of Rhode Island

Application May 8, 1947, Serial No. 138,905

Term of patent 3½ years

(Cl. D45—4)

To all whom it may concern:

Be it known that I, Eric G. O. Anderson, a citizen of the United States of America, residing at Cranston, in the county of Providence and State of Rhode Island, have invented a new, original, and ornamental Design for a Terminal Link for an Expansible Wrist Watch Bracelet, or Similar Article, of which the following is a specification, reference being had to the accompanying drawing, forming part thereof:

Fig. 1 is a top plan view of a terminal link for an expansible wrist watch bracelet or similar article showing my new design;

Fig. 2 is an enlarged perspective view; and

Fig. 3 is an enlarged end view thereof taken from the right of Fig. 1.

I claim:

The ornamental design for a terminal link for an expansible wrist watch bracelet or similar article, as shown.

ERIC G. O. ANDERSON.
